UNITED STATES PATENT OFFICE.

WILLIAM WINKELMAN, OF LOS ANGELES, CALIFORNIA, ASSIGNOR OF ONE-HALF TO
A. G. BUCHMANN, OF LOS ANGELES, CALIFORNIA.

ORE-TREATING KILN.

1,319,939.

Specification of Letters Patent. Patented Oct. 28, 1919.

Application filed June 10, 1918. Serial No. 239,346.

To all whom it may concern:

Be it known that I, WILLIAM WINKELMAN, a citizen of the United States, residing at Los Angeles, in the county of Los Angeles and State of California, have invented a new and useful Ore-Treating Kiln, of which the following is a specification.

My invention relates to furnaces or kilns suitable for the treatment of low grade ores, 10 being more particularly a kiln for the deoxidation of manganese ores and the like. At the present time in handling manganese ore it is a common practice to throw all ore having less than forty per cent. of the 15 mineral therein on the dump, consequently there exist large dumps of such low grade ore which heretofore has not been shipped on account of the expense of reducing such low grade ore.

20 One of the principal objects of my invention is to produce a furnace or kiln of simple form and construction in which the low grade ores of the class described may be economically and continuously deoxidized 25 thereby producing a product which is suitable for concentration in the ordinary forms of concentrators. This object I accomplish by using a furnace of particular construction in which is placed the crushed 30 ore intermixed with carbonaceous material such as saw-dust or similar material, and the body of ore and carbonaceous material heated to a sufficient temperature to deoxidize the ore, but without melting the 35 metallic contents.

Other objects and advantages will appear hereinafter from the following specification.

Referring to the drawings, which are for 40 illustrative purposes only,

Figure 1 is a vertical sectional view of a furnace embodying a form of my invention.

Fig. 2 is a vertical sectional view of the 45 furnace shown in Fig. 1, on line 2—2, Fig. 1, and

Fig. 3 is a sectional plan view on line 3—3, Fig. 2.

50 5 designates a front wall and 6 the rear wall of a furnace having centrally located therein a heating chamber 7 which extends vertically through the furnace, being open at the top as indicated at 8. 9, 10 and 11 each designate a series of horizontally 55 arranged hollow tile forming conduits

which extend across the chamber 7, the conduits being supported between the chamber upon partitions or walls 12. The conduits 9 communicate at their forward end with a combustion chamber 13, the rear end of the 60 series of conduits 9 being in open communication with the rear end of the series of conduits 10 through a flue 14, the front end of the series of conduits 10 being in open communication with the front end of 65 the series of conduits 11 by means of a flue 15, the rear end of the series of conduits 11 being in open communication with the stack flue 16 having any suitable stack 17 connected thereto. 70

The combustion chamber is provided with a suitable door 20 through which extends an oil burner 21 for the purpose of supplying liquid fuel to the combustion chamber. 22 designates a grate and 23 an ash chamber 75 provided with a door 24 which may be used in case that wood or coal is used instead of liquid fuel above referred to.

Arranged below the conduits in the heating chamber 7 is a hopper 25, the lower 80 end of which terminates in a trough 26 in which is operated a spiral conveyer 27 for removing the contents of the hoppers hereinabove referred to, through a pipe 28.

The furnace is operated in the following 85 manner:

The ore to be treated is first crushed and mixed with carbonaceous material such as saw-dust or similar material and placed in the chamber 7. The heat is then provided 90 by means of the burner 21 which heat passes from the combustion chamber 13, through the series of conduits 9, to the flue 14, thence through the series of conduits 10, to the flue 15, thence through the series 95 of conduits 11, and out the stack flue 16 to the stack.

By conducting the heat through the mass of ore and carbonaceous material by means of conduits as above described the mass is 100 heated throughout and the deoxidation of the ore in the chamber takes place, the mass moving downwardly thereby permitting the continuous treatment of ore. The heat so provided is sufficient to cause a deoxidation 105 of the ores being treated, but is not sufficient to melt the metal content of the ores.

It is to be noted that during this heating operation that the air is excluded from the heating chamber due to the fact that the 110

large body of material in the chamber about the conduits has a mass of fresh material in the chamber 7 above the conduits, the heat being supplied by the conduits.

5 As the ores are deoxidized the same are removed from the hopper 25 by means of the conveyer 26, the ore being permitted to remain in the hopper a sufficient length of time to permit the material to cool so that 10 the same may be handled. By the use of the kiln above described I am able to treat the low grade ores which at the present time are being thrown on the dump and place such ores in a condition to be commercially 15 handled at a profit.

My invention plays an important part in a novel method of separating manganese ores from their gangue. There exist in nature large bodies of low grade manganese 20 ore in which the manganese dioxid is mixed with silicates. Such ore is very difficult to concentrate as the dioxid is friable and when crushed tends to form a powder which cannot be separated from the silicates by ordinary 25 gravitational methods. In my new method I deoxidize the ore in the novel furnace described herein. The manganese oxid is somewhat heavier, firmer and more metallic than the dioxid and when crushed can 30 be readily separated by ordinary jiggling methods from the silicates with which it is associated.

My furnace is novel in that at all times during its operation it is filled with the ore 35 to be deoxidized mixed with carbonaceous material, and in that during this time the air is excluded from this charge which settles more or less continuously downwardly between the conduits 9 which supply the 40 heat necessary to carry on the process. The hopper 25 and that portion of the kiln directly above it form a cooling chamber in

which the hot ore is cooled before being withdrawn or exposed to air. This is very necessary as the ore is heated to a temperature of from 900 degrees C. to 1000 degrees C. in its passage between the conduits and if exposed to the air at this temperature it would rapidly reoxidize and thus nullify the main purpose of the invention.

What I claim is:—

1. A kiln for deoxidizing metallic ores comprising walls forming a continuous ore heating chamber through which a mixture of ore and carbonaceous material is allowed to settle, said walls having an inlet opening for said heating chamber at the top thereof and an outlet opening for said heating chamber at the bottom thereof, a series of conduits passing through said chamber, and means for passing a heating agent through said conduits which are imperforate so that said heating agent is kept out of contact with said ore.

2. A kiln for deoxidizing metallic ores comprising walls forming a continuous ore heating chamber through which a mixture of ore and carbonaceous material is allowed to settle, said walls having an inlet opening for said heating chamber at the top thereof and an outlet opening for said heating chamber at the bottom thereof, a series of conduits passing through said chamber, and walls forming a series of flues connecting said conduits to form a passage through which a heating agent is circulated, said passage having gas tight walls and making gas tight joints with said conduits so that said heating agent in no way comes in contact with the material being treated.

In testimony whereof, I have hereunto set my hand at Los Angeles, California, this 29th day of May, 1918.

WILLIAM WINKELMAN.
